UNITED STATES PATENT OFFICE.

BERNARD ROUS, OF BROOKLYN, NEW YORK, ASSIGNOR TO LOUIS HEFTER, OF NEW YORK, N. Y.

NECK-MAKING MACHINE.

1,098,461.

Specification of Letters Patent.

Patented June 2, 1914.

Original application filed December 4, 1911, Serial No. 663,824. Divided and this application filed May 7, 1912. Serial No. 695,628.

To all whom it may concern:

Be it known that I, BERNARD Rous, a citizen of the United States, and resident of the borough of Brooklyn, in the county of Kings 5 and State of New York, have invented certain new and useful Improvements in Neck-Making Machines, of which the following is a specification.

This invention relates to blank feeding 10 mechanism for neck making machines. It is a subdivision of my patent application for neck making machines, filed December 4th, 1911, Serial Number 663,824. In this application a complete neck making machine is 15 shown and described for the purpose of presenting the blank feeding mechanism thereof in relation to its coacting elements.

In the accompanying drawings, Figure 1 20 represents a front view of a neck making machine with the invention incorporated therewith, Fig. 2 shows a top plan view of Fig. 1, Fig. 3 is an enlarged fragmentary portion of Fig. 1, Fig. 4 represents a fragmentary top view of Fig. 3 and Fig. 5 shows 25 a right hand end view of Fig. 3.

The machine comprises the table 20 supporting the bracket 21 for the driving shaft 23. A tight pulley 28 is fastened to the shaft 23 and a loose pulley 29 is journaled thereon. A balance wheel 30 and pinion 32 is 30 fastened to the shaft 23.

Journal brackets 35, 36 and 37 extend up from the table 20 and a cam shaft 40 is journaled in said brackets. A spur gear 41 35 with the cam 42 is fastened to the shaft 40 and meshes with the pinion 32. A cam drum 43 with groove cams 44, 45 and 46 is fastened to the shaft 40. A journal bracket 48 with a plurality of bearings, and a journal 40 bracket 49 with a plurality of bearings are supported on the table 20. Spindles 50, 51, 52 are supported in the accompanying bearings of the brackets 48 and 49. To the spindle 50 are fastened the arms 55 and 56, to 45 the spindle 51 are fastened the arms 57 and 58 and to the spindle 52 are fastened the arms 59 and 60. The arms 55, 57 and 59 have respectively journaled at their upper ends the rollers 61, 62 and 63, which respectively 50 engage the groove cams 44, 45 and 46.

On the table 20 are supported the journal brackets 65, 67, and in the latter is journaled a sleeve 70 that has formed therewith a disk 71 having a notch 72. A cam 75 is fastened

to the shaft 40 and a lever 76 is pivoted to 55 the bracket 65. A roller not shown is journaled to one end of the lever 76 and at the other end of the lever is formed the toe 79, which is in the path of the notch 72.

A sector 80 on the shaft 40 can mesh with 60 a gear 81. A gear 83 on the sleeve 70 meshes with the gear 81. A tubular sleeve 86 is supported in the sleeve 70, an intermediate sleeve 87 is supported in the sleeve 86 and a third sleeve 88 is supported in the sleeve 65 87. A rod 90 is slidably supported in the sleeve 88.

A bracket 92 with the secondary bracket 93 for the rod 90 extends up from the table 20. A bracket 95 on the rod 90 supports a 70 pin 98. A link 99 has one end connected to the pin 98 and the other end is pivoted to the lever 103, which has a roller 104 to bear against the cam 42. An arm 105 carries one end of a spring 106, the other end of which 75 latter is connected to the lever 103. A collar 112 on the sleeve 86 is connected by a link 114 to the arm 60. A collar 120 on the sleeve 87 is connected by the link 122 to the arm 58. A collar 128 on the sleeve 88 is connected by 80 the link 130 to the arm 56.

The sleeve 86 carries the outer guide box 135, and an inner guide box 140 is carried by the sleeve 87. A pair of fingers 142, 143 extend from one of the walls of the box 140. 85 The sleeve 88 carries blocks 145, 146 which constitute a rectangular former. A finishing plunger 170 is connected to the rod 90. Brackets 175, 176 extend from the table 20 and carry the frame plate 177 having the 90 opening 178. The plate 177 carries the uprights 179 and 180 which are connected by the upper tie braces 183, 184 and the lower tie braces 181, 182. The upright 179 has formed therein the slot 185 for the pusher 95 block 186. A pusher plate 187 is carried on the block 186, by means of the screws 188 that extend through the slot 185. In a recess of the block 146 is pivoted a catch 151, with a spring 152 bearing against said catch. 100

On the upright 179 is fastened a threaded bracket 189 with the adjusting screw 190 having the head 191. The screw constitutes an adjustable stop for the pusher block 186. A link 192 has one end pinned to the pusher 105 block 186 and its other end is pinned to one end of the lever 193, which in turn is pinned to the tie brace 184 by means of the pin 194.

A spring 195 extends between the lever 193 and the tie brace 182.

A bell crank with the arms 196, 197 is pivoted, by means of the pin 198 to the tie brace 182. The arm 196 carries a pin 199 on which is pinned one end of the link 200, and the latter by means of the pin 201 is connected to the lever 193. The arm 197 has journalized thereto the roller 202. A cam 203 fastened to the shaft 40 is in the path of the roller 202.

A pin 204 extends from the upright 179 and a pin 205 extends from the upright 180, which respectively support the pulleys 206 and 207. A guide bar 208 is also supported on the pins 204, 205.

A sliding carriage 209 is supported on the guide bar 208 and carries the bracket 210, which has an opening for the spindle 211 of the pressure plate 212. A head 213 is carried on the spindle 211. A pin 214 extends from the carriage 209 and supports a handle 215, having the slot 216. A band 217 extends from the handle 215 passes over the pulley 206, then over the pulley 207, next under the suspended pulley 218. It carries the weight 219 and finally is fastened to the hook 200 extending from the lower face of the table 20. The carriage 209 can easily be detached from the band 217 by disengaging the slot 216 of the handle 215 from the pin 214, and then the carriage 209 can be moved by hand.

A carriage 222 is located below the brace 182. A bending arm 233 is pivoted on said carriage. A pawl 235 is pivoted on the carriage and at its upper end is pinned one end of a link 240. The other end of the latter is pinned to the lever 242 carrying the roller 245, which bears against a cam not shown.

A bracket 279 on the table 20 supports a closer 280 which is fully described in the original application. A bracket 335 for a carriage 337 is supported on the table 20. A crosshead 338 is slidably supported on the carriage 337. Blades 346, 347 that constitute shears are carried on said carriage.

An arm 364 extends from the bracket 175 and has pinned to its outer end a link 365. A bracket 366 on the table 20 has pivoted thereto the lever 368 which in turn is pinned to one end of the link 369, the other end of which latter is pinned to the link 365. A roller 370 is journalized on the lever 368, and a cam 371 on the shaft 40 is in the path of said roller. To the arm 364 is also pinned the link 372 that has journalized thereto the roller 373. A pin 374 on the link 372 is in the path of the link 365. A glue box 375 is fastened to the table 20 and has journalized therein the glue wheel 377 and spindle 379 with the cleaning blade 378. A pair of wheels 387 for the paper band 389 are journalized below the glue box. A leg 390 has

pivoted thereto an arm 392 with the counterweight 393, which forces a presser finger 394 against the band 389.

A band 403 with the weight 404 has one end fastened to the link 372. It passes over the sheave 402 journalized in the arm 401 extending from the said glue box. A supporting plate 405 is hinged to the arm 364. To operate the machine the paper band 389 is led from its reel until it reaches the carriage 222, over the edge of which latter it is bent by the bending arm 233.

A plurality of paste board strips 421 preferably notched at 422 to enable them to be shaped to form the necks or frames to be formed are located between the tie braces 181, 182 and 183, 184. The pressure plate 212 bears against said strips by virtue of the resulting effect of the weight 219 and the sliding carriage 209 maintains them with the requisite frictional engagement between said plate and the upright 179.

The shaft 23 is rotated by means of a belt not shown engaging the pulley 28. The pinion 32 and gear 41 transmit rotation to the cam shaft 40. The sector 80 rotates the gear 81 and the latter rotates the gear 83 by virtue of which the guide boxes 135, 140 and the blocks 145 and 146 are given their requisite intermittent rotations.

When the guide boxes 135, 140 and blocks 145, 146 are at rest and in the positions shown particularly in Fig. 3, the strips 421 are pushed down consecutively one after the other through the opening 178, by the pusher plate 187, the strip adjacent to the upright 179 being the one that is acted upon. The moving strip is thereby located alongside a pair of accompanying ends of the guide blocks 145, 146 and is guided in place by the fingers 142, 143. The strips travel to the lower end of the said sides of the said blocks and are pinched by the catch 151. The distance that the strips are pushed down is controlled by the location of the adjusting screw 190, the latter controlling the stroke of the pusher block 186.

The said pusher block is controlled by the action of the cam 203 on the bell crank with the arms 196 and 197 and the interposed linked connections. The spring 195 always tends to pull down the lever 193 that controls the movement of the pusher plate 187. After each strip has been lowered in position the pusher plate 187 rises and the paper band is glued to the strip as described in the original application.

Having described my invention what I desire to secure by Letters Patent, and claim is:

1. In a neck making machine the combination of a frame for supporting strips of material, a guide bar supported on the frame, a pulley at each end of the guide bar, a pin extending from the carriage, a

handle having a slot with the latter engaging said pin, a band extending from said handle over both of said pulleys, a weight carried by the band and a pressure plate 5 pivoted to said carriage to bring pressure against said strips.

2. In a neck making machine the combination of uprights, a pusher plate guided in one of said uprights, a pusher block connected to said plate, upper and lower braces connected to the uprights, a frame plate having an opening connected to said uprights, a driving shaft journaled in the machine, a cam on the shaft, a bell crank pivoted to the 10 lower braces, a roller journaled in one of the arms of the bell crank and in the path of said cam, a lever with one end pivoted to the upper braces and the other end pivoted to said pusher block, and a link with one end pivoted to said lever and the other end thereof pivoted to the other arm of said bell crank.

3. In a neck making machine the combination of uprights, a pusher plate guided in one of said uprights, a pusher block connected to said plate, upper and lower braces connected to the uprights, a frame plate having an opening connected to said uprights, a driving shaft journaled in the machine, a cam on the shaft, a bell crank pivoted to the 15 lower braces, a roller journaled in one of the arms of the bell crank and in the path of said cam, a lever with one end pivoted to the upper braces and the other end pivoted to the 20 lower braces, a roller journaled in one of the arms of the bell crank and in the path of said cam, a lever with one end pivoted to the upper braces and the other end pivoted to the 25 lower braces, a roller journaled in one of the arms of the bell crank and in the path of said cam, a lever with one end pivoted to the upper braces and the other end pivoted to the 30 lower braces, a roller journaled in one of the arms of the bell crank and in the path of said cam, a lever with one end pivoted to the upper braces and the other end pivoted to the

to said pusher block, a link with one end pivoted to said lever and the other end thereof pivoted to the other arm of said bell crank, a guide bar connected to the uprights, a carriage on said bar and a pressure plate pivoted to the carriage.

4. In a neck making machine the combination of uprights, a pusher plate guided in one of said uprights, a pusher block connected to said plate, upper and lower braces connected to the uprights, a frame plate having an opening connected to said uprights, a driving shaft journaled in the machine, a cam on the shaft, a bell crank pivoted to the 40 lower tie braces, a roller journaled in one of the arms of the bell crank and in the path of said cam, a lever with one end pivoted to the 45 said upper braces and the other end pivoted to said pusher block, a spring extending between said lever and one of the lower braces, a link with one end pivoted to said lever and the other end thereof pivoted to the other 50 arm of said bell crank, and an adjusting screw connected up with said upright having the pusher block and in the path of the latter to limit the length of its stroke.

Signed at the borough of Manhattan in 60 the county of New York and State of New York this 30th day of April A. D. 1912.

BERNARD ROUS.
